UNITED STATES PATENT OFFICE.

HENRY LILLEY, OF PHILADELPHIA, PENNSYLVANIA.

PROCESS OF AND MACHINE FOR MAKING PIPE-HOOKS.

SPECIFICATION forming part of Letters Patent No. 425,232, dated April 8, 1890.

Application filed January 28, 1890. Serial No. 338,364. (No model.)

To all whom it may concern:

Be it known that I, HENRY LILLEY, a citizen of the United States, residing at Philadelphia, in the county of Philadelphia and State 5 of Pennsylvania, have invented certain new and useful Improvements in the Process of and Machines for the Manufacture of Pipe-Hooks; and I do hereby declare that the following is a full, clear, and exact description of the 10 invention, which will enable others skilled in the art to which the same belongs to make and use the same.

My invention relates, first, to a process for cutting the blanks from a bar or plate of iron 15 or steel. The second part relates to a machine for twisting the blanks. The third part relates to a machine for rolling and flattening a part of the blank forming the hook.

The first part of my invention consists in 20 cutting the blanks from a flat metal plate, and is an improvement on Patent No. 390,491, granted to me October 2, 1888.

The second part consists in a combination 25 of mechanisms for twisting the blanks at a part which is afterward bent to form the hook.

The third part consists in the combination 30 of a die and roller by which the blanks are flattened at a part which is afterward bent to form the hook.

The object of my invention is to manufacture pipe-hooks by machinery at small cost 35 for labor, which I attain by the process of cutting blanks and mechanism illustrated in the accompanying drawings, in which—

Figure 1 represents a flat metal bar, showing 40 the notch cut that forms the heel and the cut which serves the blank from the bar. Fig. 2 represents the blank as cut from Fig. 1.

Fig. 3 represents the blank shaped by the 45 clamp-die and shows by dotted line where the blank is twisted. Fig. 4 represents the finished pipe-hook as made from a twisted blank. Fig. 5 is a diagram showing the manner of cutting blanks for twisting from a metal plate.

Fig. 6 is a diagram showing the manner of 50 cutting blanks for rolling from a metal plate. Fig. 7 represents a blank as cut from Fig. 6. Figs. 8 and 9 represent a blank cut from Fig. 6 after rolling. Fig. 10 represents a finished pipe-hook cut from Fig. 6. Fig. 11 represents a top view of my improved machine for shap-

ing and twisting blanks, Fig. 3. Fig. 12 is a side view of Fig. 11. Fig. 13 is a view of the twisting-lever and slide. Fig. 14 is a view of the bed in which is fitted slides Figs. 13 55 and 17. Fig. 15 is a view of the lever for operating the twist-lever. Fig. 16 represents a part of the clamping and forming die. Fig. 17 represents the slide to which is fastened the clamp or die Fig. 16. Fig. 18 is a side 60 view of my improved twisting and rolling machine, showing the opposite side from that shown in Fig. 12. Fig. 19 is an end view of the machine. Fig. 20 is a longitudinal sectional view of the die for rolling the blanks 65 shown in Figs. 7, 8, and 9. Fig. 21 is a top view of the die shown in section, Fig. 20. Fig. 22 is views of part of the clamping-die, which in connection with Fig. 16 forms the shaping and holding die while twisting the blank 70 shown in Fig. 3.

Similar letters of reference in the drawings represent same parts in the several views.

As above stated, the first part of my invention is an improvement on Patent No. 75 390,491, which present improvement enables me to cut blanks from metal plates and form these blanks by machinery into hooks that may be used for the largest size pipes that are supported by hooks. 80

A represents the hook-blank, which, when cut from a bar, is as shown in Figs. 1 and 2. The only waste is that part cut from notch B. When cut from a metal plate as shown in Fig. 5, the waste will be the part marked D and D'. 85 When cut from a plate as shown in Fig. 6, the waste will be that part marked D, Fig. 6.

The clippings D are not a total waste, but may be utilized for various purposes.

The machine to be employed to cut blanks 90 from the plates shown in Figs. 5 and 6 is similar to the machine used to cut large nails from plates. The cutters will be in two parts, one cutter to cut on the lines *a a a a* and the other to cut a straight line *b*, (for Fig. 5.) After 95 cutting a blank from the plate the plate is turned over right hand to left, and another blank is cut. After cutting the blanks from plate Fig. 5 they are then cut on the dotted lines shown in Fig. 5, which cuts off the waste-piece D'. This cut forms the point *d* of the shank A. The blanks are then heated red-

hot and placed in a clamping-die, (to be hereinafter described,) which die forms the blank to a shape shown in Fig. 3, and while in the clamp-die the shank A is twisted (by machinery hereinafter described) at the dotted line, putting the edge of shank A in line with the flat part of hook C. The point d is then bent over to the center of the shank A, as shown in Fig. 4. The hook C is then turned to shape shown in Fig. 4, making a complete and finished pipe-hook.

By the above process pipe-hooks of the largest size may be made from bar or plate, and except of the large size hooks the blanks will 15 only have to be heated when shaping in the die and twisting the center for the shank.

When cutting blanks from plates Fig. 6, two knives will be used, one in shape of line a a, the other knife in shape of line b. The 20 plate is turned after cutting each blank, as described for Fig. 5.

The blank A, as shown in Fig. 7, is heated red-hot and placed in a proper die, (to be hereinafter described,) which holds it while 25 passing under a roller, which roller and die flattens the part C and straightens the part A to a shape shown in Figs. 8 and 9. The part C is then, while cold, bent to form shown in Fig. 10, making a finished pipe-hook. The 30 only heating required is while rolling the part C, except when cutting blanks from thick plates to make large hooks, when it may be required to heat the plates red-hot to cut the blank from thick plates.

35 My improved machine for shaping, twisting, and rolling the hooks is constructed as follows:

Figs. 11, 12, 18, and 19 show a machine constructed after the form of a metal-planing machine, having a bed made to slide on shears. This bed is operated by a crank and connecting-rod driven by a pair of bevel-wheels and cone-pulley. The machine is provided with a shaft E, upon which is mounted a roller F 45 and a spur-wheel G, which wheel gears into a toothed rack H, fastened to the bed W of the machine. To the bed W is fixed by countersunk head screws or bolts the bed P. (See Fig. 14.) This bed is fitted for two slides N and O. (See Figs. 14 and 17.) The slide N carries the twisting-lever R. The slide O carries the clamp-plate S. (See Figs. 11 and 16.) The clamp-plate T (shown in Figs. 11 and 22) is fastened by screws to the bed H. (See 55 Fig. 11.)

L is a hand-lever. One end is connected to a toggle-joint M. One part of this toggle-joint is connected to slide O, the other part to bed P.

60 V is a lever. One end is connected to a bracket or stand Y, fastened to the bed W. The lever V is connected to lever R at J. The free end of lever V is turned up and rounded at that end, as shown in Figs. 12 and 15.

X, Fig. 11, is a loose roller mounted on a stud fixed to the frame of the machine.

f is a roller mounted on a stud fastened to the slide N.

K is a fixed-cam fastened to the body of the 70 machine by stands p p. The clamp-plate T is made so as not to cover the width of the bed H, (see Fig. 11,) but leave a ledge g.

B', Figs. 20 and 21, represents a steel die, which is to be fastened to the bed W by 75 countersunk head screws or bolts.

The operation of my improved machine is as follows: In shaping and twisting the blanks such as shown in Fig. 2, the blank is heated 80 red-hot and by tongs placed between the clamps S and T, bringing the notch B against the corner h of clamp S, and the shank A will rest on the ledge g of bed H. The hand-lever L is then moved toward the rack H. This

85 closes the clamps S and T. The blank being hot, will readily take the form of the clamps S and T, which will give the blank the form shown in Fig. 3. The machine is then started,

when the part C of the blank will be run under the roller F and the free end of lever V will 90 be raised up by the roller X, which will in turn raise at J the lever R and depress the other end, and it pressing down on the shank A turn it over the ledge g and twist the shank at the dotted line of Fig. 3, and as the lever R passes under the roller F the roller f

95 on slide N will come against the fixed cam K, which cam and roller will force the head of lever R hard up against the shank A, and the twist will be set. When the bed W has 100 moved the blank from under the roller F, the clamps S and T are opened by the lever L, the blank formed and twisted removed, and another heated blank put in the clamps, shaped, and twisted, as before described.

To roll the blanks shown in Figs. 7, 8, and 9, the bed P, with its slides and levers L and V, are removed from the bed W and the steel die B', Figs. 20 and 21, is fixed to the bed 105 W and so adjusted to the roller F as will cause the roller F to flatten and press the part C into the die and form it half-round, as shown in section, Fig. 9, the blank being red-hot when placed in the die, and at each stroke of the bed W the roller F and die B' will 110 form a blank the shape shown in Figs. 8 and 9.

115 It is understood that a pair of clamp-plates S and T are required for each size of blanks and hooks made of the form shown in Figs. 2, 3, and 4, and a die B' for each size of blank and hooks made in form as shown in Figs. 7, 8, 9, and 10.

120 The hooks can be made from wrought-iron or a cheap grade of steel, and, as above shown, from bar or plate. The hooks, after being made, may be dipped in paint, or they may be galvanized, so as to prevent rust.

125 Having as above fully described my process and machine for making pipe-hooks, what I claim as my invention, and desire to secure by Letters Patent, is—

1. The process of cutting pipe-hook blanks from a flat metal plate by first cutting the part D to form the heel and point of the next succeeding blank to be cut, as shown and described.
- 5 2. The process of cutting pipe-hook blanks from a flat metal plate by first cutting the part D to form the heel of the next succeeding blank to be cut, as shown and described.
- 10 3. In a machine for shaping and twisting pipe-hook blanks, the combination of a reciprocating bed carrying a pair of forming-clamps, with one of the clamps so fixed to the bed as to form a ledge g, a twisting-lever operating on a slide moved by a lever V and
- 15 roller X in part, and further moved by a fixed cam and roller f on the slide carrying the twisting-lever, and a pressing-roller mounted on a shaft with a driving spur-wheel operated by a toothed rack fixed to a reciprocating bed, as shown and described.
- 20 4. In a machine for rolling and shaping pipe-hook blanks, a die, as shown in Figs. 20 and 21, with a reciprocating bed, pressure-roller, operating spur-wheel, and toothed rack, as shown and described.

HENRY LILLEY.
